UNITED STATES PATENT OFFICE.

ERNEST N. LIVERMORE, OF PORT TOWNSEND, WASHINGTON.

DESIGN FOR A VIOLIN.

SPECIFICATION forming part of Design No. 26,423, dated December 22, 1896.

Application filed October 31, 1896. Serial No. 610,763. Term of patent 14 years.

To all whom it may concern:

Be it known that I, ERNEST N. LIVERMORE, a citizen of the United States of America, residing at Port Townsend, in the county of Jefferson and State of Washington, have invented a certain new and useful Design for the Shape of a Violin, of which the following is a specification, reference being had therein to the accompanying drawings.

10 This invention relates to designs for violins, violas, and violoncellos; and it consists in the shape or configuration to be hereinafter duly described, shown, and claimed.

In illustrating the invention reference will 15 be had to the accompanying drawings, forming part of the specification, which contain like reference-characters in each of the views.

Figure 1 is a top plan view of a violin. Fig. 2 is a sectional view on the line *x-x* of 20 Fig. 1.

In the drawings, 1 denotes a violin of the shape illustrated in the drawings, my inven-

tion residing in the arrangement of the curved arm 2 in connection with the body. The body of the violin, as shown, extends upward in a 25 curved shape and lies against the head of the finger-board. The section view illustrates the shape of the top and bottom where the arm joins the body, from which it will be seen that the walls approach until the point 3 is 30 reached, when they are caused to diverge at about the same angle.

Having fully described my invention, what I claim as new, and desire to secure by Letters Patent, is—

The design for a violin, substantially as herein shown and described.

In testimony whereof I affix my signature in presence of two witnesses.

ERNEST N. LIVERMORE.
